HAT

Germaine Montabert, New York, N. Y.

Application October 30, 1950, Serial No. 12,772

Term of patent 7 years

(Cl. D3—13)

To all whom it may concern:

Be it known that I, Germaine Montabert, a citizen of the United States, residing in New York city, in the county of New York and State of New York, have invented a new, original, and ornamental Design for a Hat, of which the following is a specification, reference being had to the accompanying drawing, forming part thereof.

Fig. 1 is a side perspective view of a hat showing my new design.

Fig. 2 is a top plan view thereof.

Fig. 3 is a bottom plan view, and

Fig. 4 is a fragmentary enlarged view illustrating the detail of the interlaced brim portion.

The interlacing indicated in Figs. 1 and 3 and shown in detail in Fig. 4 extends throughout the outer face of the turned up brim.

I claim:

The ornamental design for a hat, substantially as shown and described.

GERMAINE MONTABERT.
